SPIRAL ROTARY SHIP OR SIMILAR VESSEL

Filed May 29, 1928

JOSEPH C. BECHARD

Manuel C. Rosa

Attorney

UNITED STATES PATENT OFFICE.

JOSEPH C. BECHARD, OF FALL RIVER, MASSACHUSETTS.

SPIRAL ROTARY SHIP OR SIMILAR VESSEL.

Application filed May 29, 1928. Serial No. 281,566.

My invention relates to a new and useful type of boat which spins through the water, the boat being waterproofed throughout so that water passing overhead does not enter 5 the interior. Unlike the submarine this boat is intended for use on the water but by reason of its peculiar construction it is adapted to cut its way through waves or breakers with a minimum amount of resistance. The speed 10 which may be attained with this model illustrated in the drawing is enormous.

The boat, hereinafter described and illustrated in the accompanying drawings, is an improvement upon the spiral rotary ship, 15 patented to me by Letters Patent Number 1,665,012, and dated April 3, 1928.

It is an object of my invention to provide a boat of the ellipsoidal type wherein the outer shell is caused to revolve around on the keel, 20 the shell having spirally disposed vanes on its surface to accelerate its speed ahead. The internal arrangement is such that the compartments within are independent of and do not revolve with the shell. A stabilizing keel 25 is provided upon which the boat turns.

A further object of my invention is to provide a driving means for rotating the outer shell of the boat which comprises a circumferential gear disposed internally of said outer shell and being adapted to coact with the driving gear of an engine or some other motive power.

A still further object of my invention is to provide a spiral rotary ship of the character 35 described, wherein the keel is provided with a stabilizing means which is capable of being operated or controlled from the pilot house. More particularly, the said stabilizing means comprises fin members hingedly secured to 40 the sides with control means running from the pilot house to each of said fin members whereby they may be regulated in the manner necessary for the proper running of the boat.

45 Other objects and advantages will appear from the detailed description which follows:

I attain these objects and advantages by means of the mechanism illustrated in the drawings wherein:

50 Figure 1 is a side elevational view of my ship showing the ellipsoidal outer shell mounted on the keel, the spirally disposed vanes on said shell also being shown.

Figure 2 is a front elevational view of the front end of the ship. 55

Figure 3 is a cross sectional view of one of the ends of the ship showing the manner of mounting the ship for rotation of the exterior shell while the inner shell remains stationary.

Figure 4 is a cross sectional view taken 60 through the keel adjacent the fin members and showing the gear members for controlling the fin members.

Figure 5 is a cross sectional view taken 65 through the keel at a still lower point to show the mounting of the fin members on the keel.

Similar numerals refer to similar parts throughout the several views.

Referring to the drawings, 1 is the outer shell of the ship substantially ellipsoidal in 70 design and being mounted for rotary movement on its ends which are journaled on the tubular members 2 and 3 which are secured to the keel 4. The shell 1 may be constructed of wooden lagging or sheet metal, or, in fact, any 75 suitable material, reinforcing means may be used internally thereof to strengthen the same.

As both ends of the boat are alike it will be only necessary to describe one end of the 80 mechanism to show the manner of relative movement between the moving shell and the fixed tubular end. At the open end of the outer shell an end member 5 is secured. Disposed between this end member of the outer 85 shell and the tubular member 2 are the bearings 6 and 7. A stuffing box 8 is provided at the outermost extremity of the end member and a facing strip 9 is attached to the end member and overlies the outer shell. The 90 end member 5 is provided at its innermost extremity with a circumferential gear 10.

Disposed within the revolvable outer shell is the inner stationary shell 11 which is of shorter length and is fixedly mounted to the 95 inner ends of the tubular members 2 and 3. The motive power (not shown) is placed within this fixed compartment or shell, but its driving shaft 12 passes through a bearing member 13 in the end wall of the inner 100 shell to a point without and is of such length that a driving gear on the end of said shaft is adapted to mesh with the teeth of the circumferential gear member 10 which is secured to the outer shell.

105 It will be appreciated that by the turning

of the shaft 12 with the corresponding driving gear 14 that the outer shell will be made to rotate, the speed of rotation depending upon the number of revolutions. The propulsion of the boat is accelerated by means of the spirally disposed vanes 15.

At the inner end of the end member 5 is provided the partition members 30 and 31 which are respectively secured to the end 10 member and the tubular end 2 with a stuffing box 32 at their jointure to retain the lubricant for the driving gear.

With reference to the keel 4, the tubular ends 2 and 3 are secured to the keel as shown 15 in Figure 1. A pilot house may be placed at each end of the keel and means may be had within the pilot house for controlling the rudder 16 and the stabilizing means 17. A suitable exhaust pipe 35 may be provided as 20 shown. As shown in Figure 2 the keel tapers downwardly, the fin members 18 being shown extended outwardly.

I will now speak with reference to the stabilizing means 17 which is shown in Figure 3 and more particularly in Figures 4 and 5. The stabilizing means comprises the fin members 18 which are disposed on each side of the keel in the pockets 19 provided therefor. The fin members are provided with 30 split collar portions 20 at the head ends, which in addition to being secured to said head ends surround the rods 22 and 23 which pass through the keel as shown in Figure 1. The rods 22 and 23 are held in hinged relation by means of the straps or bands 21 (see Figure 1) which are secured to the keel and allow clearance for the rods to move the fin members in and out. It will be seen that the fin members are held in hinged relation to 40 the keel. The rods 22 and 23 extend upwardly a distance about half way between the stabilizer and the pilot house (see Figure 3) and they are provided on their upper ends with gear members 24 and 25. Control rods 45 26 and 27 run from said pilot house down to points adjacent said gears 24 and 25 and are provided with pinions 28 and 29 which mesh with said gears and manipulate the same upon the turn of the control rods within the 50 pilot house. The necessary deflection of the fin members, in order to stabilize the keel, is generally not very great and by the means proposed it may be regulated minutely and steadily. As may be seen from Figure 1 the 55 means for controlling the stabilizer is enclosed within the keel.

The mode of operation of the rotary ship is as follows. The driving force is applied to the driving gear from a motor or engine 60 within the stationary compartments of the ship and the driving gear in turn, meshes with the teeth of the gear means which is circumferentially disposed on the outer movable shell and causes it to rotate. The revolution of the outer shell in the water causes

the spiral vanes to cut the water and to propel the ship ahead. By reason of its tapered ends the ship is suited to readily cut through waves and breakers without materially reducing its speed. The shell may be provided with a 70 transparent surface at some portion of its surface to provide illumination for the interior, however, this is optional.

All that has been said above in the description of my preferred embodiment is offered 75 by way of illustration and not limitation. I do not wish to be limited to the exact structure of the preferred embodiment shown and described, or to any particular material used 80 in the construction of parts, or to the design of parts, but desire protection as against any variations in structure or substitution of equivalents which utilize the principle of my invention and fall within the purview of my 85 invention and are within the spirit and scope of the following claims.

The invention having been set forth, what is claimed as new and useful is:

1. A self contained rotary ship comprising a keel, an ellipsoidal shell mounted for 90 axial movement on said keel, spirally disposed vanes on said shell, a stabilizing means at the bow portion of said keel, said stabilizing means comprising fin members disposed on each side of said keel bow, separate control 95 means within said boat for controlling each of said fin members.

2. A self contained rotary ship comprising a keel, an ellipsoidal shell mounted for axial movement on said keel, stabilizing means at the bow portion of said keel, said stabilizing means comprising fin members hingedly secured to said keel portion, said fin members having rod portions secured thereto and extending upwardly, said rod portions being provided with gear members at their upper extremities and control rods for each of said rods, said control rods having a gear means at the lower extremity to mesh with the gears on the rods, said control rods being adapted to move said fin members through the gear means set forth.

3. A boat comprising an imperforate shell, a keel, said shell being mounted for axial rotation on said keel, means on said shell for propelling said boat, said means comprising a driving means within said boat adapted to coact with means circumferentially disposed within said shell, stabilizing means on said keel, said stabilizing means comprising fin members disposed on each side of said keel, control means within said boat for controlling each of said fin members.

4. A self contained rotary ship comprising a keel, tubular ends secured to said keel, a shell of ellipsoidal shape mounted for axial movement on said tubular ends, spirally disposed vanes on said shell, a circumferential gear disposed interiorly of said shell, driving means within said boat for coacting with said

circumferential gear to rotate said shell, stabilizing means at the bow portion of said keel, said stabilizing means comprising fin members hingedly secured to said keel portion, said fin members having rod portions secured thereto and extending upwardly, said rod portions being provided with gear members and their upper extremities and control

rods for each of said rods, said control rods having pinions at the lower extremity to mesh 10 with the gears on the rods, said control rods being adapted to move said fin members through the gear means set forth.

In testimony whereof I have affixed my signature.

JOSEPH C. BECHARD.
